AUTOMOBILE WIND DEFLECTOR

Harry A. Reichman, Chicago, Ill.

Application October 18, 1951, Serial No. 17,003

Term of patent 7 years

(Cl. D14—6)

To all whom it may concern:

Be it known that I, Harry A. Reichman, a citizen of the United States, residing at Chicago, in the county of Cook and State of Illinois, have invented a new, original, and ornamental Design for an Automobile Wind Deflector, of which the following is a specification, reference being made to the accompanying drawing, forming a part hereof.

In the drawing:

Fig. 1 is a perspective view of an automobile wind deflector, embodying my new design;

Fig. 2 is an elevational view as seen from the outer side thereof;

Fig. 3 is a top plan view of the same;

Fig. 4 is an elevational view of my new design for a car ventilator as seen from the inner side thereof; and

Fig. 5 is an edge elevational view as seen from the left hand side of Fig. 4.

I claim:

The ornamental design for an automobile wind deflector, substantially as shown.

HARRY A. REICHMAN.
